UNITED STATES PATENT OFFICE.

MARMADUKE M. M. SLATTERY, OF NEW YORK, N. Y.

DESIGN FOR A FILAMENT.

SPECIFICATION forming part of Design No. 15,839, dated February 17, 1885.

Application filed November 4, 1884. Term of patent 7 years.

To all whom it may concern:

Be it known that I, MARMADUKE M. M. SLATTERY, of the city of New York, in the county and State of New York, have invented and produced a new and original Design for Filaments for Incandescent Lamps, of which the following is a specification, reference being had to the accompanying drawing, forming part hereof.

10 The drawing shows the filament when viewed from the front, displaying the design, the whole of which is in the same vertical plane, or substantially so.

The general form of the design is that of a 15 curvilinear four-pointed star, two of the re-entering angles being more obtuse than the others, and all its angles being curves.

The configuration of the design will be un-

derstood by a reference to the drawing, wherein in the outline or profile of the approximately 20 star-like form is shown. The form of the space inclosed within the filament will thus be that of a stem or standard having thereon star-like members or projections divided by curvilinear re-entering angles. 25

I claim—

The design for the shape or configuration of a filament, consisting of a star-like outline having curvilinear members or projections and re-entrant angles, as shown and described. 30

In witness whereof I have hereunto set my hand this 25th day of September, 1884.

MARMADUKE M. M. SLATTERY.
